UNITED STATES PATENT OFFICE.

ARTHUR H. CHASE, OF WASHINGTON, DISTRICT OF COLUMBIA, ASSIGNOR TO THE GOVERNMENT OF THE UNITED STATES.

SWIRL REDUCER.

Application filed November 2, 1920. Serial No. 421,412.

To all whom it may concern:

Be it known that I, ARTHUR H. CHASE, a citizen of the United States, residing at Washington, District of Columbia, have invented new and useful Improvements in 5 Swirl Reducers, of which the following is a specification.

This invention relates to improvements in torpedo tubes and more particularly to 10 means adapted to reduce or eliminate the swirl produced in firing submerged submarine torpedo tubes.

The torpedo tubes carried by modern submarines are located below the water line and 15 the torpedo is ejected from the tube by means of compressed air. This compressed air is admitted near the breech of the torpedo tube and acts behind the torpedo to force the same outwards. After the torpedo 20 is once started the propelling mechanism goes into operation and the torpedo will travel under its own power. The initial impulse given by the compressed air is considerable and a large amount of this air 25 passes out from the tube and blows on the surface of the water producing a swirl visible from some distance away from the submarine thus disclosing its exact location and enabling the enemy to fire on the submarine 30 or drop depth charges or otherwise take up the pursuit of the boat from the swirl marking as a starting point.

With this understanding in mind, the 35 present invention is designed to eliminate or reduce this swirl as much as possible thereby rendering the location of the submarine discharging the torpedo as near trackless as possible.

A further object is to provide a simple 40 and practical mechanism of the above general character adapted to control the flow of air to and from torpedo tubes.

A further object is to provide a device of 45 the above character which may be easily applied to torpedo tubes now in use without material addition or alteration.

A further object is to provide a device of 50 the above character which may be readily adjusted for operation at different degrees of submergence and which may be easily cut in and out of use as desired.

Other objects will be in part obvious and 55 in part hereinafter pointed out.

Reference has been made to the accom- 60 panying sheets of drawings showing the

present device as applied to a torpedo tube in sufficient detail for those skilled in the art to readily manufacture and install the same.

In the accompanying drawings forming 60 part of the disclosure and wherein similar reference characters denote corresponding parts,—

Figure 1 is an elevational view showing the device applied to the lower one of two 65 submarine tubes.

Figure 2 is an end sectional elevational view taken substantially on the line 2/2, Figure 1.

Figure 3 is a partial sectional view showing 70 the device in normal position with the parts in normal or low pressure position.

Figure 4 is a view similar to Figure 3 with the parts in high pressure or firing 75 position.

Figure 5 is a sectional view taken substantially along the line 5/5, Figure 4.

Figure 6 is a sectional view taken substantially along the line 6/6, Figure 3.

Figure 7 is a detail perspective view of 80 the outer sleeve of the valve shown in Figures 3 and 4.

Figure 8 is a sectional plan view taken substantially on the line 8/8, Figure 1.

Referring now to the drawings in detail 85 and more particularly to Figure 1, 10 and 11 denote respectively the upper and lower torpedo tubes of a submarine. The present device is connected with and operates the lower tube 11 only, a similar device being 90 applied to each of the other tubes.

The firing mechanism comprises broadly a check valve 12, Figure 8, adapted to admit air to the lower torpedo tube 11, air coming 95 from any suitable source of supply such as a reservoir through the main air pipe 13. A valve 14 is adapted to coact with seat 15 and is operated by handwheel 16 to entirely shut off the mechanism hereinafter described when so desired. Associated with the check valve 12 is a firing valve 17 and a differential piston 18 connected by means of pipe 20 with the swirl reducer 21, Figure 1, the opposite side of the swirl reducer being provided with a pipe connection 22 leading to a pilot valve 23 which exhausts into the atmosphere when the firing mechanism indicated by rod 24 is moved relatively 100 towards the left, Figure 1, to actuate a valve stem 25. The swirl reducer is also con- 105

nected by means of pipe 26 with the firing reservoir; this connection may be to the main reservoir.

Referring again to Figure 8, it will be noted that the valve 17 is normally held closed by means of the spring 27 coiled about a stem 28 of the differential piston 18. This stem 28 is connected with a handle 30 passing through an oil reservoir or other 10 hydraulic cylinder 31 which is adapted to regulate the rate of opening of the valve 17. The piston 18 is provided with a slight clearance whereby air may leak past from the source of supply in pipe 13 to the rear 15 of the differential piston thereby tending to keep the valve 17 closed, air pressure acting both on the valve 17 and the inner surface of the piston 18.

Referring now to Figure 3, the valve casting 21 is provided with two chambers 32 and 33 separated by a partition 34 having a by-pass or opening 35. Within this member 21 is a sleeve 36 and a longitudinally movable piston valve 37 normally urged to the position shown in Figure 3 by means of coil spring 38. This piston valve 37 is connected by means of a stem 40 with a handle 41 whereby it may be reciprocated by hand in order to test the operativeness of the parts 30 prior to firing.

Reference to Figure 4 will show that the spring 38 coiled about the stem 40 rests on an adjustable nut 42 which may be moved in and out by means of handwheel 43 to determine the amount of air pressure necessary to move the parts from the position shown in Figure 3 to that shown in Figure 4. A suitable scale 44, Figure 3, is provided to indicate the degree of tension placed upon 40 the spring. The coating parts 36 and 37 are provided with ports 46 and 45 respectively, communicating with the pipe 26 when the parts are in the position shown in Figure 3. When pressure is admitted 45 through this pipe 26 to act upon the member 37 this member is then moved relatively towards the left to compress the spring 38 and cause valve 47 to rest firmly on its seat 48 thereby preventing any leakage to the 50 atmosphere.

When this pressure is admitted through the pipe 26 and the parts moved to that position shown in Figure 4, ports 50 and 51 in the chamber 33 are then in register thereby 55 establishing communication between the pipes 20 and 22.

With this construction in mind it is believed that the following statement of operation will render the objects more apparent.

As the air reservoir is being charged the pressure therefrom passes in through pipe 26, ports 45 and 46, bypass 35 and pipe 20, thus building up pressure below the piston 18, this pressure holding the valve 17 to its

seat Fig. 8. This action continues until the air reservoir pressure overbalances the spring 38 at which time the piston valve 37 is forced from the position shown in Fig. 3 to the position shown in Figure 4. The normal air reservoir pressure is greater than the pressure at which this action of the piston valve 37 takes place and when the valve 14 is opened by means of the handwheel 16, air pressure from the reservoir passes through the pipe 13 and gradually leaks past the piston 18 thus building up pressure below this piston to the full reservoir pressure. This pressure also then exists in pipe 20 and in the swirl reducer valve shown on 75 Figure 4, its escape to the atmosphere being prevented by the pilot valve 23 Fig. 8. When the tube is fired the rod 24 Fig. 1 moves relatively towards the left and opens the pilot valve 23 by engaging the stem 25 allowing the air pressure within the system to instantly fall. The opening of this pilot valve results in a reduction in pressure back of the piston 18 Fig. 8 to a point much below the pressure on the forward side of the piston or the pressure in the pipe 13. This by reason of the differential action causes the firing valve 17 to open and the air pressure passes through the valve 12 into the tube and ejects the torpedo therefrom.

As soon, however, as the pressure in the pipe 13 falls due to its admission to the torpedo tube then the pressure in pipe 26 also connected with the same source of supply, drops correspondingly and instantly allows the sliding valve 37 to move from the position shown in Figure 4 back to that shown in Figure 3 under the action of the spring 38 thereby cutting off further passage of air from the pipe 20 to the pipe 22 and the pilot valve from whence the air escapes to the atmosphere. Pressure immediately builds up again in the pipe 13 after the firing of the torpedo and the air rushing in through pipe 26 and ports 45 and 46 Figure 3, by-pass 35 and pipe 20 again restores the firing valve 17 due to the differential pressures upon the piston 18 to closed position thus cutting off a further supply of air to the tube through the valve 17 and check valve 12. This train of operations takes place almost instantly and just enough air is admitted to the tube at the rear of the torpedo to start the same on its way from the tube.

From the above it will be seen that the present invention provides a most simple, practical, reliable and efficient mechanism for automatically admitting the proper amount of air to the tube to accomplish the desired firing function.

The device is substantially automatic in its operation and not only is more economic in the use of air but primarily reduces or substantially eliminates the objectionable

swirl heretofore found in submarine firing of torpedoes.

Without further analysis, the foregoing will so fully reveal the gist of this invention that others can by applying current knowledge readily adapt it for various applications without omitting certain features that, from the standpoint of the prior art, fairly constitute essential characteristics of the generic or specific aspects of this invention, and therefore such adaptations should and are intended to be comprehended within the meaning and range of equivalency of the following claims.

15. What I claim is:—

1. In an apparatus of the character described, in combination, with the torpedo tube, a source of air pressure, a normally closed firing valve, a swirl reducer valve 20 and a pilot valve, said swirl reducer valve adapted to disconnect the pilot valve from the firing valve at the moment of firing and admit air pressure to the opposite side of the firing valve to close the same.

25. 2. In an apparatus of the character described, in combination, with the torpedo tube, a source of air pressure, a normally closed firing valve having a differential piston, a pilot valve, and a swirl reducer valve 30 interposed between said differential piston and the pilot valve adapted to close path of communication between the pilot valve and the firing valve on the opening of the firing valve and admit pressure to the rear 35 of said differential piston to again close the firing valve.

3. In an apparatus of the character described, in combination, with the torpedo tube, a source of air pressure, a normally closed firing valve having a differential piston, a pilot valve, a pipe connecting the rear 40 of the differential piston with the pilot valve, a swirl reducer valve in said pipe and providing a normally open path of communication to the pilot valve and means for closing said path of communication on opening the firing valve and admitting compressed air to the rear of said differential piston to again close said firing valve.

45. 4. In an apparatus of the character described, in combination with the torpedo tube, a source of air pressure, a normally closed firing valve having a differential piston, a pilot valve, a pipe connecting the

rear of the differential piston with the pilot 55 valve, a swirl reducer valve in said pipe and providing a normally open path of communication to the pilot valve, and means for closing said path of communication on opening the firing valve and admitting compressed air to the rear of said differential piston to again close said firing valve, said swirl reducer valve comprising a casing having two chambers and two sets of valves one 60 in each chamber, one set being normally open and the other normally closed, said chambers having a communicating passage therebetween.

5. A swirl reducer valve associated with the firing mechanism of submarine torpedo 70 tubes comprising a casing divided into two communicating chambers, a valve in each chamber, one valve being open and the other normally closed, and a firing valve, a source of compressed air for holding said first mentioned valves in normal position and means including a pilot valve whereby said valves alternate their open and closed position on firing the torpedo and again assume their normal position after firing.

6. A swirl reducer valve associated with the firing mechanism of submarine torpedo tubes comprising a casing having two communicating chambers, a tubular member 85 mounted in said chambers and provided with ports, a longitudinally movable valve member positioned in said tubular member having ports registering with the ports in one chamber and normally out of register with the ports in the other chamber, a spring 90 urging said movable member in one direction and a source of compressed air urging said movable member in the other direction, said spring being adapted to close one set and open the other set of ports when said 95 air pressure is reduced on firing and a firing valve and a pilot valve between which said swirl reducer valve is interposed.

7. In combination with a submarine torpedo tube, a pilot valve, a firing valve and 100 automatically operating means adapted to open and close said valve when the torpedo is fired, said means including a swirl reducer valve interposed between the firing valve and the pilot valve.

Signed at Washington, District of Columbia, this twenty second day of June 1920.

ARTHUR H. CHASE.
